United States Patent Office

Des. 184,867
Patented Apr. 14, 1959

184,867

SPOON OR SIMILAR ARTICLE

Richard C. Gavette, Southington, Conn., assignor to Wallace Silversmiths, Inc., Wallingford, Conn., a corporation of Connecticut

Application August 20, 1958, Serial No. 52,299

Term of patent 14 years

(Cl. D54—12)

Fig. 1 is a front view on an enlarged scale of a spoon showing my new design;

Fig. 2 is a rear view thereof;

Fig. 3 is an edge view thereof;

Fig. 4 is a section taken on line 4—4 of Fig. 1; and
Fig. 5 is a section taken on line 5—5 of Fig. 1.

I claim:

The ornamental design for a spoon or similar article, substantially as shown.
